UNITED STATES PATENT OFFICE.

FRANCIS M. VOLK, OF MINTURN, CALIFORNIA.

RAIL-JOINT AND ANTICREEPING DEVICE.

No. 858,235.

Specification of Letters Patent.

Patented June 25, 1907.

Application filed November 1, 1906. Serial No. 341,568.

To all whom it may concern:

Be it known that I, FRANCIS M. VOLK, a citizen of the United States, residing at Minturn, in the county of Madera and State of California, have invented new and useful Improvements in Rail-Joint and Anticreeping Devices, of which the following is a specification.

My invention relates to a combined rail chair, rail joint and anti-creeping device.

It consists of the parts and the construction and combination of parts as hereinafter more fully described and claimed, having reference to the accompanying drawings in which,

Figure 1 is a perspective view of the device. Fig. 2 is a vertical section of same; and Fig. 3 is a plan view.

A represents a rail having its base flange, adjacent to an end of the rail, cut out as shown at 2, correspondingly with the lugs 3 on the base plate of the chair 4. The latter is open at one side as shown to permit of the laying and removal of the rail. The closed side or fixed angle plate 5 of the chair is shaped to fit over one side of the base flange of the rail and abut against and support one side of the web of the rail.

The open side of the chair has a lengthwise extending flange 6, behind which the rail will fit when the opposite side of the base flange of the rail is properly seated in under the closed flange 5. The inner side of the shallow flange 6 has a longitudinal groove 7 into which the hook-shaped end 8 of the movable angle plate 9 is adapted to fit hinge fashion. The fixed angle plate 5, the removable angle plate 9 and the web of the rail, are correspondingly perforated as shown at 10, so that with the rail in place, and with the angle plate 9 engaged in its interlocking recesses 7 and turned up against the side of the rail and the

parts bolted together through these perforations 10, the removable angle will be drawn toward the fixed angle clamp-fashion to grip 45 the rail and prevent any rattling at the joint.

The base of the chair may be perforated as shown at 11 to allow the same to be securely spiked or bolted to the ties, and the rails may be provided with the spike holes 12 for holding the rail to the ties for proper spacing.

The cut out portions 2 of the rail and the interlocking lugs 3 of the chair, are for the purpose of preventing any creep of the rails or track due to expansion and contraction.

Having thus described my invention, what I claim and desire to secure by Letters Patent is—

1. The combination of a rail chair having a base portion and a fixed integral angle plate, said base portion having a flange between which and said fixed angle plate the rail is adapted to seat, and a movable angle plate having its outer edge turnably fitted to the inner wall of the flange of the chair.

2. A rail chair having a base portion provided with upwardly extending lugs adapted to fit corresponding recesses in the base flange of a rail to prevent the rail from creeping, and said base portion having a fixed integral angle plate, and a removable angle plate, said base portion of the angle plate having a flange and said removable portion of said angle plate having its outer edge hingedly mounted to the inner wall of the flange of the 75 fixed angle plate.

In testimony whereof I have hereunto set my hand in presence of two subscribing witnesses.

FRANCIS M. VOLK.
